UNITED STATES PATENT OFFICE.

SOLOMON M. MILLER, OF PEORIA, ILLINOIS, ASSIGNOR, BY MESNE ASSIGNMENTS, TO
ELEVATOR LOCKS COMPANY, OF PEORIA, ILLINOIS, A CORPORATION OF ILLINOIS.

SAFETY APPLIANCE FOR ELEVATORS.

1,144,966.

Specification of Letters Patent. Patented June 29, 1915.

Application filed November 22, 1909. Serial No. 529,493.

To all whom it may concern:

Be it known that I, SOLOMON M. MILLER, citizen of the United States, residing at Peoria, in the county of Peoria and State of Illinois, have invented certain new and useful Improvements in Safety Appliances for Elevators; and I do hereby declare that the following is a full, clear, and exact description of the invention, which will enable others skilled in the art to which it appertains to make and use the same.

This invention pertains to safety locks for the starting lever of passenger and freight elevators and relates more particularly to locking means for said starting lever controlled by the floor or shaft door.

The primary object of the invention is to provide a mechanism having the above in view and in which part of such mechanism is carried by the said car and part by the building-floor.

Another object is to improve upon the device shown in my Letters Patent No. 1,017,684 issued to me on the 20th day of February, 1912, by providing new forms of certain of the parts whereby advantages may be had.

The invention besides having these objects in view relates to certain details of construction which will be pointed out herein and form the subject matter of some of the appended claims.

In the appended drawings:—Figure 1 is an elevation of part of the mechanism used inside of the elevator-car with parts in broken lines and in which the floor of the car is shown in part section. Fig. 2 is a plan of part of the car and a part of the building-floor showing the mechanism carried by each. Fig. 3 is a transverse section of part of the car and part of the building-floor, showing their respective mechanisms. Fig. 4 is a sectional elevation, in part, of an arm carried by the car to extend through the side thereof. Fig. 5 is a side elevation of an adjustable connection for certain of the parts. Fig. 6 is an elevation of part of the car showing mechanism for operating a door locking device. Fig. 7 is an elevation of part of the building-floor showing the door locking device. Fig. 8 is a plan of the two mechanisms shown in Figs. 6 and 7.

The drawings illustrate a controlling or starting lever for the elevator-car and means to lock it in the opening movement of the

floor-door. The parts operated by the door in its opening movement will lock the operating lever at its position of rest or where it has no control of the power. Therefore, if the door is open the lever in the car must be held so that the operator is powerless to start the car.

A indicates the floor of the building in which the elevator car is installed, and B represents the floor of the elevator-car itself, while C and D indicate the elevator-door and the door-track respectively. Mounted in any suitable manner upon the floor A between the elevator-shaft and the track D is a standard E having two vertical extensions F, Fig. 7, through which extends a horizontally disposed slideable bar G having an adjustable member H thereon, Figs. 2 and 7, provided with a roller J extending into said elevator-shaft, said member being secured in any desired position by means, for example, of a set screw K. Secured also upon the floor some distance from the standard E is a member L' shown in another position in Fig. 3. It is provided with a head L² and two ears M thereon which carry a rock-shaft O on which is an arm N. Secured on the projecting end of said shaft lying nearest the door C, see Figs. 2 and 7, is a fork P in position to be engaged by a roller Q carried by the said door. Upon the upper end of the arm N is pivoted a block R provided with a set screw S; there being a rod T carried at one end in said block and secured by said screw, while the opposite end of the rod has pivotal connection with the slideable bar G hereinbefore described.

It is the purpose of this device, as in my Letters Patent above mentioned, to lock the operating mechanism in the car by means operated by the shaft-door, that is to say, when the door is opened said mechanism will be operated to cause the controlling lever or other member in the car to be held so that it cannot be moved to start said car. The mechanism as carried by the car, and which is somewhat different from the form shown in my patent referred to, will now be described.

I have indicated the starting lever of the car at 5. Adjacent to said lever is a rock-shaft 6 mounted in bearings 7 secured on the floor of the said car, said shaft being bent to form an arch shaped portion 8 provided with a notch 9 to receive said lever 5. One

end of the shaft is provided with an upwardly extending arm 10, which, when moved, rocks the shaft to embrace said lever.

Journalized upon the wall of the car is a vertically disposed rock-shaft 11 the bearings therefor being indicated at 12. Secured on the said shaft is an arm 13 lying substantially parallel to the shaft 6 the free ends of said arm and shaft being connected, for instance, through a link adjustable for length in any desired manner. This may consist, for instance, of a threaded member 14 engaging yoke-members 15 pivoted to blocks 16 carried by both the arms 10 and 13. This adjustment is provided so that a given movement of the arm 13 will impart the proper distance of movement to the part 8 to properly engage the lever 5; while a spring 17 on the arm 13 normally tends to hold the said part 8 free of said lever. The shaft 11 is provided near each end with an arm 18, one of which is shown in Figs. 2 and 3, both said arms extending through the wall of the car. They carry at their ends outside the car, a vertically disposed striking plate or bar 19 whose ends are formed with angling extensions 20. This said bar travels with the car and between said car and the wall of the elevator-shaft, and is adapted to be engaged by the roller J on the sliding rod G. When the car has a position at the floor and the shaft-door is moved to open it the fork P is engaged by the roller Q to impart movement to the bar G. The roller J of the latter thus engages the bar 19 and rocks the shaft 11 to move the arm 13 in a direction to cause the part 8 of the rock-shaft 6 to inclose the lever 5 and thus prevent its movement sufficient to start the car, while the door is open. But in closing the door the roller J is carried away from the bar 19 and the spring 17 of the arm 13 will at once rock the shaft 6 to its normal position thus permitting the lever 5 to be operated. It is to be noted that the width of the notch 9 of the said part 8 is considerably greater in measurement than the width of the lever. The purpose of this is, that though said lever may not stand exactly at its central position, though powerless to start the car, it can be readily engaged by said part 8.

The difference in structure over my former device, and the advantages arising therefrom as to ease of operation and simplicity of construction it is believed are apparent.

At this time I desire to point out the fact that the mechanism for locking the operating lever due to the movement of the door is absolutely positive since the mechanism is engaged directly by the door when the same is opened. Furthermore, there is no noise due to parts striking one another during the movement of the elevator-car from floor to floor. The roller J and the member 19 are never permitted to touch in the travel of the

car but one is brought into the path of the other only at the time the car is to be stopped to open the door. The said member 19 extends above and below the said roller J so that the starting lever can be locked even when the car is slightly above or slightly below said floor level. The mechanism operated by the door and the means on the car which engages it move in parallel planes parallel to the plane of the door and the side of the car instead of in a direction perpendicular to the plane of the door, or across the space between the car and the door as in some of the older devices. A nice adjustment of the engaging parts is thus possible which would not be true in said older structures. In addition, I am enabled to adapt the device to a car in which the operating lever may work in some other plane than that parallel to the door since the required locking operation can be transferred to it through any suitable members.

It is evident that the parts of my mechanism may be altered in various ways to suit requirements or to satisfy the desires as to the best manner of accomplishing the various operations and all without departing from the spirit and intent of the invention; all such changes lying within the meaning thereof.

It is to be understood that my mechanism is adaptable to all types of car starting or operating means whether that means is in the form of a lever, wheel, or other device and for the sake of brevity of description herein and in some of the claims this starting means has been referred to as a "lever."

Also those parts referred to hereby by the numerals 18, 19 and 8 for locking the operating lever 5, though made up of several parts, and which may be mounted otherwise than shown, will be referred to in the claims as a "rocking member" in the interest of clearness and brevity since these could be slideable parts as well as rocking ones.

I have used the term "lock" in speaking of the control of the lever 5 by means of the member 8 and shall use the same or an equivalent term in some of the claims and while the said member 8 does not actually "hold" or "lock" the lever that member cannot be moved sufficiently to start the car when the said member 8 is thrown toward it.

In referring to the arched portion or part 8 in some of the claims I shall state that it is moved into the path of the starting device or lever 5. By this I mean any means that will engage the device or lever or in some way prevent its movement to start the car by moving into the path of movement of said lever or some part of it.

Besides the mechanism which forms the subject of this application other mechanism is illustrated which relates to a door lock but this forms the subject matter of a divi-

sional application No. 640,303 filed July 24, 1911.

Having thus described my invention, I claim:—

- 5 1. In mechanism of the class described, the combination with an elevator-car, of a starting lever therein, a rocking member adapted to maintain the starting lever in its inoperative position, a second member carried by 70
10 the car and extending into the elevator-shaft and adapted for pivotal movement in a lateral direction and having operative connection with the rocking member, a device to elastically and normally hold the rocking member removed from the path of the starting 75
15 lever, the floor door, a member mounted upon the building-floor and engaged and moved by said door, and adjustable means on the last named member to engage the described second member carried on the car. 80
20 2. In mechanism of the class described, the combination with an elevator-car, of a starting lever, means carried by the car adapted to be rocked into the path of the starting 85
25 lever to station it in its position of rest, a member pivotally mounted on the car and extending into the elevator shaft and provided with an obliquely disposed extension at each end, said member adapted for a 90
30 rocking movement in a lateral direction and having operative connection with the rocking means, a device to elastically hold the rocking member removed from the vicinity of the starting lever, the floor door, a member mounted upon the building-floor and engaged and shifted by said door, an adjustable 95
35 extension on the last named member to engage the pivoted member, and means to fix the extension in position on said member. 100
40 3. In mechanism of the class described, the combination with an elevator-car, of a controlling lever for the same, rocking means mounted on the car and provided with a recess to receive the said controlling lever, a 105
45 lever extension on the rocking member, a member carried by the car and extending into the elevator-shaft and having a lever-extension to operatively connect with the extension of the said rocking member, a device 110
50 for normally holding the latter and the second named member at one extreme of their movements, the floor door, an extension thereon, a rock-shaft, a member on said shaft with which the extension of the door engages, a horizontally disposed slidable member, means on the building-floor to carry the latter, means to operatively connect said slidable member with the said rock-shaft, and an extension on the said slidable member to engage the member on the car that extends into the elevator-shaft. 115
55 4. In mechanism of the class described, the combination with an elevator-car, of an operating lever therein, means in the car adapted to move into the path of said operating 120
60 65

lever and having a lever-extension thereon, a vertically disposed shaft having bearings on the wall of the car, a lever thereon operatively connected to the said lever-extension, an extension on said shaft projecting into the elevator-shaft including a member provided with a vertically disposed surface, said member having an extension at each end disposed at an angle to the vertical surface, a device to normally hold the lever engaging means at one of its extreme positions, the floor door, a standard mounted on the building-floor, a member carried by and movable relatively thereto, a rocking-member operatively connected to the latter 80
75 to shift it, an extension on the door to engage and move the rocking member, and an adjustable part on the member carried by the standard adapted to engage the member on the car having the vertically disposed surface. 85

5. In mechanism of the class described, the combination with the elevator-car, of a starting lever therein, a rocking member adapted to move into the path of the said lever and maintain it inoperative, a member carried on the car disposed vertically within the elevator-shaft and having an oblique extension at each end, a standard mounted on the building floor, a horizontally shiftable member therein, a friction roller carried thereby adapted to engage the said vertically disposed member, and a floor door adapted to engage and move the shiftable member to impart movement to the vertically disposed member. 95
100

6. In mechanism of the class described, the combination with the elevator-car, of a starting lever, means in the car to hold the lever, a member operatively connected with the said means and extending into the elevator-shaft and shiftable in a lateral direction, means to adjust the first said means and the said member relatively, the elevator-door, a shiftable member mounted on the building-floor to which movement is imparted by and parallel to said door, and a roller carried by the shiftable member and adjustable thereon and adapted to engage the member on the car for the purposes set forth. 105
110

7. In mechanism of the class described, the combination with the elevator-car, of a starting lever therein, means in the car to hold the lever, a member carried on the car and operatively connected with said means and extending into the elevator-shaft, means to adjust the first said means and the member relatively, the elevator-door, a shiftable member mounted on the floor to which movement is imparted by said door, an extension 120
125 on the door, and a member engaged thereby and having operative connection with the shiftable member, means by which the two are adjusted relatively, and an adjustable roller carried by the shiftable member and 130

adapted to engage the said member on the car.

8. The combination with an elevator-car, its starting lever, and the floor door, of means in the car to lie in the path of the starting lever including a member extending into the elevator-shaft, a standard on the building floor, a member carried thereby and provided with an extension adapted for adjustment longitudinally thereof parallel to the door to engage the first described member, a forked rocking member mounted on the floor, a link connecting the rocking member and the member carried by the standard, and a projection on the door to engage the said forked rocking member.

9. The combination with an elevator car, its starting lever, and the floor - door, of means carried by the car and adapted to be rocked into the path of the lever and having an arm, a bell-crank pivoted on the car, a link connecting the arm with one of the extensions of the bell-crank, a substantially vertically disposed striking-plate carried by the other extension of the bell-crank, and a member operated by the floor-door in its opening movement adapted to engage and move said striking plate to move the means in the car into the path of the lever.

10. The combination with an elevator-car, its starting lever, and the floor - door, of means carried by the car and adapted to be rocked into the path of the lever and having an arm, a bell-crank pivoted on the car, a link connecting the arm with one of the extensions of the bell-crank, a substantially vertically disposed striking-plate carried by the other extension of the bell crank and lying within the elevator shaft, and means operated by the floor-door in its opening movement adapted to engage and move said striking plate to move the said means in the car into the path of the lever, the ends of said striking plate receding at an obtuse angle from one of its surfaces and when at rest lying substantially parallel to the side of the car from which it is carried.

11. The combination with an elevator car, its starting lever, and the floor - door, of means carried by the car and adapted to rock toward and into the path of the said lever, a member mounted on the car and lying in the elevator shaft including a part to operate said means, a link connecting the said part and said means, a device constantly tending to elastically hold the latter disengaged from the lever, the said member having its ends receding at an angle from one of the surfaces in the direction of its line of movement, a support mounted on the building-floor, a member mounted therein and adapted to be shifted parallel to the floor door by the movement of the door and including a part to engage said member, a fork mounted near the door and adapted to

swing parallel to and by said door and including an arm, and means connecting the said arm and the shiftable member.

12. The combination with an elevator car, its starting lever, and the floor door, of means in the car adapted to be carried into the path of the lever, a member operatively connected therewith and lying in the elevator shaft and including a vertical portion, a support mounted on the building floor, a member carried by it and movable parallel to the plane of the door, and adapted to engage and move the part on the car and lying in the elevator shaft, a fork mounted also on the floor and operated by said door, a part connecting the fork and the said member, and means to permit adjustment of the fork and the member relatively.

13. The combination with the starting device of an elevator car, of a rock - shaft mounted in the car provided with an offset portion including a notch to engage said device, a bell crank mounted on the car, a link connecting one of its arms with said rock-shaft, a vertically disposed striking plate mounted on the other arm of said bell crank outside the car, a shaft door, and means operated by it adapted to move said striking plate.

14. The combination with the starting device of an elevator car, of a rock - shaft mounted in the car provided with an offset portion including a notch to engage said device, a bell crank mounted on the car, a link connecting one of its arms with said rock-shaft, a vertically disposed striking plate mounted on the other arm of said bell crank outside the car, a shaft door, means operated by it adapted to move said striking plate, and means to elastically hold the latter in the direction of the last named means.

15. The combination with the starting device of an elevator car, of a rock - shaft mounted in the car provided with an offset portion including a notch to engage said device, a bell crank mounted on the car, a link connecting one of its arms with said rock - shaft, a vertically disposed striking plate mounted on the other arm of said bell crank outside the car, a shaft door, and means operated by it adapted to move said striking plate, including an adjustable part to engage the latter.

16. A standard, a bar slidable therein, a sliding door including a part extending laterally therefrom, a fork pivoted in the path of the said part and adapted to receive the latter, an arm extending from the pivot of the fork, and a link pivotally connecting the arm and said bar, in combination with an elevator car including a starting device, and means on the car to engage the latter including a part operated by said bar in one of the movements of said door.

17. A standard, a bar slidable therein, a

sliding door including a part extending laterally therefrom, a fork pivoted in the path of the said part and adapted to receive the latter, an arm extending from the pivot 5 of the fork, and a link pivotally connecting the arm and said bar, in combination with an elevator car including a starting device, means on the car to engage the latter including a part operated by said bar in one of the

movements of said door, and a member 10 elastically in control of the said means.

In testimony whereof I affix my signature, in presence of two witnesses.

SOLOMON M. MILLER.
